SIGN DEVICE

Arsène A. Perry and Hermann A. Weber,
Springfield, Mass.

Application July 5, 1933, Serial No. 679,033

7 Claims.

(Cl. 40—89)

Our invention relates to improvements in sign devices, and more particularly to that type of sign device intended for use as a display for prices, and capable of change to correspond to changes in prices.

An object of our invention is to provide a sign device in which fractional prices may be displayed, and in which the whole figures and the fractional figures may be varied at will, and independently of each other.

A further object of our invention is to provide such a sign device which will display identical, or the same, prices, on each side thereof at all times, and so arranged that the prices on one side cannot be changed, without also changing them on the opposite side correspondingly.

A still further object of our invention is to provide such a sign having means therein for illuminating the symbols, or figures, at night in such a manner that the sign may be as easily read at night, as by day.

These, and other objects and advantages of our invention will be more particularly described and disclosed in the specification, the accompanying drawings, and the appended claims.

Broadly, our invention comprises a suitable casing member having windows on opposite sides, shafts extending longitudinally through the casing member above and below the windows, means on the shafts below the windows for manually revolving the shafts, tension springs mounted on the shafts above the windows, a plurality of rollers fixedly secured on each of the lower shafts, a plurality of rollers slidably secured on the springs on each of the upper shafts and to which the springs are secured, and curtain sign members on said rollers, the curtains on the rollers on any one shaft being wound in opposite directions, and means within the casing for illuminating the exposed backs of the curtain members.

A preferred embodiment of our invention is illustrated in the accompanying drawings, in which:

Fig. 1 is an elevational view of our sign device showing one side.

Fig. 2 is a vertical, longitudinal section through the axis of the rollers.

Fig. 3 is a partial, detail, sectional view of one of the upper rollers.

Fig. 4 is a partial, sectional view on the line 4—4 of Fig. 2.

Fig. 5 is a cross, or transverse, sectional view on the line 5—5 of Fig. 2.

Figs. 6 and 7 are diagrammatic views, illustrating the winding and operation of the curtains and rollers.

Fig. 8 is a partial, elevational view of the curtain having printed thereon whole numbers, and

Fig. 9 is a view similar to Fig. 8, showing the

curtain having printed thereon fractional numbers.

Referring now to the drawings in detail, in which like numerals refer to like parts throughout:

The casing 1 comprises the frame portion 2, side portions 3 and 4, and top member 5. The frame 2 is made from a single strip of sheet metal bent to form the bottom 6, ends 7 and 8, and top 9. The sides 3 and 4 are formed with window openings 10 and 11, and 12 and 13, respectively. The opening 12 is not shown in the drawings, but is understood as being opposite the opening 11, in Fig. 1. The openings 10 and 11 are separated by the dividing metal strip 14, and the openings 12 and 13 are similarly separated. The openings 10 and 11 are covered with the transparent sheet 15, held in the frame 16, which is secured to the side 3, in any suitable manner, such as screws, solder, or spot welding. The openings 12 and 13 are covered in a similar manner with the transparent sheet 17 and frame 18. Within the casing 1, near the top, are revolvably secured the shafts 19 and 20, which are held in place with the pins 21. Coil springs 22 and 23 are loosely supported on the shafts 19 and 20. Rollers 24 and 25, formed with axial openings 26 and 27, are loosely mounted on the spring member 22, and rollers 28 and 29, formed with axial openings 30 and 31, are loosely mounted on the spring member 23. The rollers 24 and 25, and the rollers 28 and 29, are separated by means of the washers 32, which act as guards for the curtains, mounted on these rollers. A bent end 33, of the spring 22, is secured to the outer end of the roller 24 in the slot 34, (see Figs. 3 and 4), and the opposite end 35 of the spring 22 is secured in a similar manner in the outer end of the roller 25. The ends of the spring 23 are secured in a like manner to the rollers 28 and 29.

Within the casing 1, near the bottom, are revolvably secured the shafts 36 and 37. Rollers 38 and 39 are fixedly secured on the shaft 36, with the pins 36', and are separated by the guard washer 40, and rollers 41 and 42 are fixedly secured on the shaft 37 with the pins 39', and separated by the guard washer 43. Knurled knobs 44 and 45 are secured to the shafts 36 and 37, respectively, on the outside of the end member 7, and serve as means for manually operating the shafts 36 and 37.

In the embodiment of our invention, illustrated in the accompanying drawings, half of the sign is used for the display of whole numbers, as of prices, and the other half for the display of fractional numbers, as of prices. Other combinations are possible, such as whole numbers and decimal parts thereof, letters and figures, feet and inches, etc. Continuous strips of cloth, paper, or other suitable material are provided, hav-

ing printed thereon the desired symbols. For the purpose of displaying whole numbers and fractions thereof, as indicated in the drawings, two strips 46 and 47, having printed thereon whole numbers 48 in consecutive sequence, and two strips 49 and 50, having printed thereon fractional numbers 51 in consecutive sequence, are used. On the strips 46 and 49, the figures read from top to bottom, as indicated in Fig. 8, and 10 on the strips 47 and 50, the figures read from bottom to top, as indicated in Fig. 9. This is indicated in Fig. 1, by the arrows 52' and 53'. When the knob 44 is turned, the rollers 38 and 39 are operated. This causes the strips 46 to be 15 wound onto, or off, of the rollers 38 and 24. At the same time, the strip 47 is wound to or off rollers 25 and 39. By reason of the coiled spring 22, a taut effect, is provided which automatically maintains the strips 46 and 47 taut, or stretched, 20 in order to prevent wrinkles therein. This condition of the strips is maintained, whether or not the rollers 38, 24, 25 and 39 are turned, or rotated, in either direction. When the lower knob 45 is turned, the rollers 41, 42, 29 and 28 are rotated. 25 The strips 49 and 50, having fractional figures thereon, will be moved. This causes roller 29 to be rotated through the spring 23, and retained in place with the coiled spring 23. The springs 22 and 23 operate to rotate the aligned rollers 24, 25, and 28 and 29, in opposite directions. 30 It will be seen, therefore, that, when the knob 44 is turned, the strips 46 and 47, which are located on the opposites, or faces of the casing, are moved at the same time, and in opposite directions of travel. Also, when the knob 45 is moved, the fractional strips 49 and 50 are moved at the same time, and in opposite directions of travel. This arrangement makes the numerals on the sign strips readable from left to right hand, on 35 the opposite faces of the sign. 40 An electric light bulb 52 is provided through the cable 53. A wire gauze 54 prevents the strips from coming into contact with the bulb and burning the same. Suitable spaces, 55 and 56, are provided for sign names, or other readable matter. 45 What we claim is:—

1. A price display sign comprising in combination, a casing; fixed and movable shafts therein, a plurality of aligned rollers therein and loosely mounted on said fixed shafts, rollers secured to the movable shafts, strips secured to the said rollers and bearing numerals thereon, the aligned rollers having spring devices connected to their extreme outer ends for maintaining the strips 50 taut.
2. A display sign comprising in combination, a casing having openings in its opposite sides, fixed shafts in the casing, a plurality of aligned rollers in the casing and loosely mounted on said fixed shafts, strips attached to the rollers, rotatable shafts in the casing, aligned rollers secured to the rotatable shafts, some of the rollers being driving ones and the others driven through the attached strips, the driven rollers having spring means connected at their extreme outer ends for rendering the strips taut at all times.
3. A display sign comprising in combination, a casing having openings in its opposite sides, spaced rollers in the casing, strips attached to the said spaced rollers, some of the rollers being driving ones and the others driven through the attached strips, the driven rollers having spring means connected at their extreme outer ends for rendering the strips taut at all times.
4. A display sign comprising in combination, a casing having openings in its opposite sides, spaced rollers in the casing, strips attached to the said spaced rollers, some of the rollers being driving ones and the others driven through the attached strips, the driven rollers having spring means connected at their extreme outer ends for rendering the strips taut at all times.

tached strips, spring means on the driven rollers only and attached to their extreme outer ends for rendering the strips taut at all times.

5. A device for indicating prices in whole and fractional numbers comprising a casing having an opening in its opposite sides, two driving rollers in its lower end and located one above the other, two driven rollers in its upper end, located one above the other, strips connecting the rollers bearing prices thereon, the strip that is movable 10 and visible in one opening serving to simultaneously operate the diagonally disposed strip in the opening of the opposite side and in the opposite direction, said strips being movable in opposite directions, as described, and spring means 15 for maintaining the opposite strips taut, fixed shafts on which the upper rollers are located and the spring being attached to the rollers at their extreme outer ends.

6. A device for indicating prices in whole and fractional numbers comprising a casing having an opening in its opposite sides, two driving rollers in its lower end and two driven rollers in its upper end, strips connecting the rollers bearing prices thereon, the strip that is movable and 20 visible in one opening serving to simultaneously operate the diagonally disposed strip in the opening of the opposite side, said strips being movable in opposite directions, as described, and spring means on the driven rollers for tensioning the 25 strips, the construction and arrangement being such that the whole numbers and fractional numbers will read from left to right and the same on both sides of the casing.

7. In combination, in a price display sign, or the like, a casing member having a plurality of openings in its opposite sides, a plurality of rollers in the casing, upper and lower shafts on which the rollers are mounted, strips on the rollers, located for travel opposite the openings, the upper 40 rollers being loose on their shafts and the lower rollers being fixed to their shafts, means for connecting the upper rollers together, means for operating the rollers and strips thereon from the shafts on which the rollers are fixed, the strips 45 that are diagonally located relative to each other on opposite sides of the casing being simultaneously moved and in opposite directions, some of the strips bearing whole numbers and the others fractional numbers, whereby the said numbers 50 will read from left to right on the opposite sides and will display the same numbers on the opposite sides of the casings through the openings.

8. A changeable sign device comprising in combination, a casing having openings in its opposite sides, two fixed and two rotatable shafts in the casing, two aligned rollers loosely located on each of the fixed shafts, means for spacing the rollers from each other, a spring on each of the fixed shafts having its opposite ends connected 60 to the outer ends of the aligned rollers, two rollers secured to each of the rotatable shafts, strips bearing numeral characters connecting the 65 loosely mounted rollers and the rollers that are fixed to the rotatable shafts, the construction and arrangement being such that the strips on opposite sides will be moved in opposite directions when the rotatable shafts are turned, as described.
